(57) **CLAIM**

The ornamental design for back and seat cushions for a chair, as shown and described.

DESCRIPTION

FIG. 1 is a perspective view showing the top, left side and front of a chair having the back and seat cushions which form my new design, the broken lines of other parts of the chair and a ground line illustrated in this and/or other figures being for illustrative purposes only and forming no part of my design;

FIG. 2 is a left side elevational view thereof;

FIG. 3 is a right side elevational view thereof;

FIG. 4 is a front elevational view;

FIG. 5 is a rear elevational view thereof; and,

FIG. 6 is a top plan view thereof.
